UNITED STATES PATENT OFFICE.

AUGUST HENKEL, OF NEWARK, NEW JERSEY.

NAIL-FILE.

No. 825,212.

Specification of Letters Patent.

Patented July 3, 1906.

Application filed March 7, 1905. Renewed May 26, 1906. Serial No. 318,953.

To all whom it may concern:

Be it known that I, AUGUST HENKEL, a citizen of the United States of America, residing at Newark, in the county of Essex and State of New Jersey, have invented new and useful Improvements in Nail-Files, of which the following is a specification.

This invention relates to nail-files, and has for its objects to produce a comparatively simple inexpensive device of this character in which the file or blade may be readily folded into its handle when not in use and one wherein the blade may be readily opened for use and maintained rigidly in its open position.

With these and other objects in view the invention comprises the novel features of construction and combination of parts more fully hereinafter described.

In the accompanying drawings, Figure 1 is a side elevation of the file embodying the invention, showing the same in open position. Fig. 2 is an elevation showing the device folded. Fig. 3 is an elevation, partly in section, the section being taken centrally and longitudinally through the handle.

Referring to the drawings, 1 designates the handle, composed, preferably, of sheet metal and folded throughout its length at its transverse center to produce a pair of spaced side plates 2 and a rigid connecting portion or back 3, the side plates being recessed, as at 4, at a point adjacent the rear end of the handle.

Pivotaly connected with the handle 1 is a file-blade 5, of any appropriate form and material, having an inner end extension 6, provided with a diagonally-inclined slot 7, having a continuous marginal roll and designed to receive a pin 8, entered transversely through and riveted or otherwise secured in the side plates 2 of the handle at a point adjacent the forward end of the latter, it being apparent from this arrangement that the blade is slidably and pivotally at the same time permanently connected with the handle 1.

In practice when the blade is open, as in Figs. 1 and 3, it will be moved inward relative to the handle until the pin seats at the forward end of the slot 7, thus bringing the adjacent edge of the extension 6 into firm

contact with the back 3, whereby the blade 50 will be maintained rigidly in its open position, it being apparent that in order to close the blade it is first necessary to move the latter forward relative to the handle, whereby owing to the diagonal inclination of the slot 7 55 the inner bearing edge of the extension 6 will move out of contact with the back 3, thus to permit of the blade being closed. In this connection it is to be noted that the inner or pivoted end of the blade is slightly rounded, 60 as at 9, and that the width between the rounded edge 9 and adjacent end of the slot is less than the distance between the pin 8 and back 3, thus permitting of the pivotal movement of the blade in closing. 65

From the foregoing it is apparent that I produce a simple inexpensive device in which the blade may be readily closed or opened and one wherein when in the latter position the blade will be held rigidly relative to the 70 handle, it being understood that in obtaining these ends minor changes in the details herein set forth may be resorted to without departing from the spirit or scope of the invention. For example, while I have herein described the device as applicable to nail-files it will be obvious that the pin-and-slot connection may be employed in various other instruments equipped with a foldable blade. 75

Having thus described the invention, what 80 is claimed as new is—

A device of the class described, comprising a handle having a rigid back and a foldable blade, one of said parts being provided with an inclined slot having a continuous marginal 85 wall and the other a fixed pin entered through said slot for permanently attaching the blade slidably and pivotally to the handle, said slot serving through movements of the pin therein to positively move the blade transversely 90 into and out of contact with the back of the handle.

In testimony whereof I affix my signature in presence of two witnesses.

AUGUST HENKEL.
